UNITED STATES PATENT OFFICE.

ANTON WALTERBACH, OF SOUTH MILWAUKEE, AND LOUIS HEIL, OF MARSHFIELD,
WISCONSIN.

FLY-PROTECTOR FOR SCREEN-DOORS.

No. 884,547.

Specification of Letters Patent. Patented April 14, 1908.

Application filed October 11, 1907. Serial No. 396,883.

To all whom it may concern:

Be it known that we, ANTON WALTERBACH, of South Milwaukee, Wisconsin, and LOUIS HEIL, of Marshfield, Wisconsin, have invented 5 a Fly-Protector for Screen-Doors, of which the following is a specification.

This invention relates to devices for preventing insects, and more particularly flies, from gaining access to the interior of a room over the top of the door when the door is 10 open.

Experience shows that flies tend to gather on the outside of a wire screen-door near the top, and when the door is opened they 15 fly up over the top of the door and enter through the opening at the top. Our invention is designed to provide an auxiliary screen which at all times covers this opening at the 20 top of the door without interfering with the opening and closing of the latter. We further aim to produce such a device which shall be simple and cheap in application and shall not require any noticeable additional effort in opening the door, shall not interfere 25 with the closing of the same by a door-closer or spring, shall not be in the way of persons going out and in, and shall not form a large or unsightly excrescence upon the door or frame.

30 With these and other objects in view our invention consists in the combination and arrangement of parts, as will be hereinafter more fully described, shown in the accompanying drawings, and particularly pointed 35 out in the appended claims; it being understood that changes in the form, proportion, size and minor details may be made within the scope of the claims without departing from the spirit or sacrificing any of the advantages of the invention.

40 In the appended drawing, Figure 1 is a perspective view of a screen door and door-frame having our invention attached thereto. Fig. 2 shows in plan view the frame work of 45 our invention.

In these drawings every reference letter refers always to the same part.

The drawing shows a door-way comprising a door *a* and a frame consisting of jambs *b* and 50 *c* and lintel *d*, the door being mounted upon hinges *e*. Over the top of the door is mounted a fan-shaped arrangement consisting of a number of ribs *f* pivoted upon a pin *g* mounted in ears *h*, the pin *g* being set in vertical 55 position and in line with the pivotal axis

upon which the door turns. Over the frame-bars or ribs *f* is laid a flexible fabric *i* which may be secured to said ribs by means of holes *j* therein. An upright bar *k* is set on the upper edge of the door and on the outer 60 face of same, in such manner that it does not interfere with the lintel in closing, but acts as an abutment for the ribs *f* and prevents them from extending over the outside of the door.

65 It will be obvious that the protector as described will be effective in preventing the entry of flies over the top of the door, and will also not interfere with the opening and closing thereof. It also interferes as little as 70 possible with appearances. However, to further protect the opening of the door against the ingress of flies, we provide a fringe of loose cords or ribbons *m* depending from the outer edge of the fabric *i*, which are cut off 75 about five feet six inches above the floor, that is at such height that they will just graze the average person's head without causing annoyance. In this manner the whole opening is effectively closed, as the flies will not enter 80 the lower portion of the opening through which the person is passing, being scared away by his movement.

85 We wish it understood that the fabric *i* is not essential to our invention, as the bars *j* would form a very effective screen, when properly connected together, especially if made wide enough to fully overlap each other. The fringe *m*, while useful, is also not essential. If used, the ribs *f* should be made to 90 project beyond the edge of the door as shown, so that the fringe will be held away from the opening and not interfere with the door in closing.

95 Having thus described our invention what we claim as new and desire to secure by Letters Patent is:

1. A fly-protector for doors, comprising a plurality of over-lapping ribs pivoted on a single axis and adapted to be set over the 100 door with said axis in line with the axis of the door-hinges, means for attaching the lowermost rib to the door and the uppermost to the door-frame and a fringe of pendent objects loosely depending from the outer 105 ends of said ribs.

2. A fly-protector for doors comprising, in combination with the door and frame, a plurality of ribs pivoted on a single axis in line with the pivotal axis of the door, and a 110

flexible fabric mounted thereover and connected at one side with the door and at the other with the frame.

3. A fly-protector for doors comprising, in combination with the door and frame, a plurality of ribs pivoted on a single axis in line with the pivotal axis of the door, a flexible fabric mounted thereover and connected at one side with the door and at the other with the frame, and a fringe of objects loosely depending from the outer edge of said fabric to a certain distance above the floor.

4. A fly-protector comprising, in combination with a door and frame, a folding fan shaped arrangement consisting of ribs pivoted on a vertical axis at one side of the door and having fabric covering them and connected at one side to the door and at the other to the frame, and an upright bar projecting above the door and acting as an abutment for said ribs.

5. A fly-protector for doors consisting of a plurality of folding members one over the other pivoted on a single axis on the hinged side of the door and above the latter and so connected to the door and frame and to each

other as to move equally upon each other in opening of the door forming a protective covering for the opening above the door; and an upright bar on the door above and outside the door acting as an abutment for said folding members. 30

6. A fly-protector for doors comprising, in combination with the door and frame, a plurality of ribs pivoted on a single axis in line with the pivotal axis of the door, a flexible fabric mounted thereover and connected at one side with the door and at the other with the frame, and a plurality of depending cords attached to the outer edge of 40 the device and depending to a certain distance above the floor.

In witness whereof, we have hereunto set our hands in presence of two witnesses.

ANTON WALTERBACH.

LOUIS HEIL.
